UNITED STATES PATENT OFFICE.

PAUL BORRMANN, OF BERLIN, GERMANY.

WOODEN PROPELLER.

1,012,507.

Specification of Letters Patent.

Patented Dec. 19, 1911.

Application filed February 7, 1911. Serial No. 607,037.

To all whom it may concern:

Be it known that I, PAUL BORRMANN, a subject of the German Emperor, and residing at Berlin, Germany, have invented certain new and useful Improvements in Wooden Propellers, of which the following is a specification.

My invention relates to wooden propellers for airships, flying-machines and the like.

10 Wooden propellers for aerial craft are already well-known having blades comprising narrow boards running in the direction of the blades. In these propellers the boards are superposed in the shape of a fan and 15 then glued together in layers at right angles to the axis of rotation, whereupon they are worked into the required shape of the blade. This known mode of manufacture has various disadvantages:—Firstly, as is well-known, in the case of air-propellers it is exceedingly important to make the section of the blade as thin as possible and, particularly, to make the ends as sharp as possible. When the known mode of gluing the boards 20 together was employed, however, after obtaining the correct spiral shape there remained at the outer ends of the blades so few glued joints that they could not be made as thin as was required. Secondly, it 25 is well-known that it is preferable to make the two blades of one propeller at a small definite angle to one another, in order to negative not only the action of centrifugal force, but also that of the thrust of the 30 blades. Such a slanting position of the blades could not be obtained when the propellers were made in the manner known heretofore. In this event a large portion of the outer ends of the blades would have been 35 robbed of its connection with the hub owing to wedge-shaped pieces being formed, there being, in addition, no continuous wood fibers running from the end of the blade to the hub.

40 A primary object of my invention is to provide a wooden propeller, to which these defects are not attached.

According to my invention the two opposite blades of a propeller consist of continuous wooden rods which run in the direction of the blades and, in contradistinction to the blades known heretofore, are glued 45 one with another in layers parallel to the axis of rotation of the propeller. In this

manner I obviate the above mentioned disadvantages and obtain, in addition, the advantage that the number of the glued joints is considerably increased just at the places subjected to the greatest breaking strain. In this manner greater strength and security from warping is obtained particularly owing to its being possible to connect together a large number of pieces of wood having the grain in various directions.

One illustrative embodiment of my invention is represented in the accompanying drawing, wherein:—

Figure 1 is a plan of a complete propeller, comprising two blades, Fig. 2 is a section, enlarged, on the line A—A in Fig. 1 and Fig. 3 is a plan, enlarged, showing the outer end of a blade, parts of the veneers being broken away.

Referring to the drawings, my propeller comprises a plurality of flat wooden rods or bars *a* which run in a direction longitudinally of the blades proper of the propeller and are disposed in layers, said layers being extended in a direction parallel to the axis of rotation of the propeller. These wooden rods are made according to a templet having the form of the blade and are firmly glued together. In order to give the blades greater strength and stiffness, I glue on both sides of each blade transverse veneer *b* and over the latter longitudinal veneer *c*, whereby the resistance to the influences of the weather is also simultaneously increased.

I claim:—

1. A wooden propeller of the character described, consisting of wooden bars which run in the direction of the blades of the propeller and are glued one with another in layers, said layers being extended in a direction parallel to the axis of rotation of the propeller.

2. A wooden propeller of the character described, consisting of wooden bars which run in the direction of the blades of the propeller and are glued one with another in layers, said layers being extended in a direction parallel to the axis of rotation of the propeller, a transverse veneer arranged at right angles to the rods and glued on both sides of the blades, and a longitudinal veneer arranged at right angles to said transverse veneer glued on the latter, substantially as shown.

3. A wooden propeller of the character described consisting of flat wooden bars which run in a direction longitudinally of the blades proper of the propeller, and are glued one with another in layers, said layers being extended in a direction parallel to the axis of rotation of the propellers.

In testimony whereof, I affix my signature in the presence of two witnesses.

PAUL BORRMANN.
